UNITED STATES PATENT OFFICE.

THOMAS ALKER, OF PITTSBURG, PENNSYLVANIA.

DESIGN FOR A HOOK.

SPECIFICATION forming part of Design No. 31,995, dated December 19, 1899.

Application filed November 1, 1899. Serial No. 735,540. Term of patent 14 years.

To all whom it may concern:

Be it known that I, THOMAS ALKER, a citizen of the United States of America, residing at Pittsburg, in the county of Allegheny and State of Pennsylvania, have invented and produced a certain new and useful Design for a Hook, of which the following is a specification, reference being had therein to the accompanying drawings.

10 This invention relates to certain new and useful designs in hooks; and it consists in the novel and ornamental appearance of the same.

15 The invention has for its object to construct a device of this character containing distinctive features and a certain configuration that will be pleasing to the eye.

20 The invention consists in the form of the hook to be hereinafter more fully described and claimed.

In describing the invention in detail reference is had to the accompanying drawings, forming a part of this specification, wherein like numerals of reference indicate corresponding parts throughout the several views, 25 in which—

Figure 1 is a perspective view of my hook. Fig. 2 is a top plan view of the same. Fig. 3 is a side elevation of the same.

25 In the drawings the reference-numeral 1 indicates the body portion of the hook, having formed at one end a curved portion 2, terminating in an upwardly-extending curved portion 3, and a downwardly-extending curved portion 4 is formed at the other end of 35 the hook, terminating in a portion 5, extending parallel to the body portion 1.

I claim—

30 The design for a hook, substantially as herein shown and described.

40 In testimony whereof I affix my signature in the presence of two witnesses.

THOMAS ALKER.
